US0D1103062S

(12) **United States Design Patent** (10) **Patent No.:** **US D1,103,062 S**
(45) **Date of Patent:** **** Nov. 25, 2025**

(54) **AIRCRAFT CENTER CONSOLE**

(71) Applicant: **Textron Aviation Inc.**, Wichita, KS (US)

(72) Inventors: **Kenneth Grisanti**, Wichita, KS (US); **Corey Eckhart**, Bel Aire, KS (US); **Aaron Tobias**, Clearwater, KS (US)

(73) Assignee: **Textron Innovations Inc.**, Providence, RI (US)

(**) Term: **15 Years**

(21) Appl. No.: **29/912,024**

(22) Filed: **Sep. 12, 2023**

Related U.S. Application Data

(63) Continuation of application No. 29/823,514, filed on Jan. 18, 2022, now Pat. No. Des. 1,011,992.

(57) **CLAIM**

The ornamental design for an aircraft center console, as shown and described.

DESCRIPTION

FIG. 1 is a right perspective view of the aircraft center console showing our new design;

FIG. 2 is a left perspective view of the aircraft center console of FIG. 1;

FIG. 3 is a front view of the aircraft center console of FIG. 1;

FIG. 4 is a rear view of the aircraft center console of FIG. 1;

FIG. 5 is a left view of the aircraft center console of FIG. 1; FIG. 6 is a right view of the aircraft center console of FIG. 1;

FIG. 7 is a top view of the aircraft center console of FIG. 1; and,

FIG. 8 is a bottom view of the aircraft center console of FIG. 1.

In FIGS. 1-8, broken lines indicate environmental structure that forms no part of the claimed design.

1 Claim, 8 Drawing Sheets
